UNITED STATES PATENT OFFICE.

CHARLES R. HARDY, OF MOUNT VERNON, NEW YORK, ASSIGNOR TO THE SUPER-HEATER COMPANY, OF NEW YORK, N. Y.

LOCOMOTIVE SMOKE-BOX ARRANGEMENT.

Application filed June 20, 1925. Serial No. 38,527.

My invention relates to locomotives and has particular reference to the steam piping arrangements in and around the smoke-box of the locomotive, to provide the necessary steam supply to one or more of the numerous auxiliaries with which modern locomotives are equipped.

For the operation of some of the locomotive auxiliaries, such as feed water and air pumps, live steam is required, while exhaust steam may be utilized by others such as feed water heaters or exhaust steam injectors. In the case of the latter auxiliaries it is the usual practice to obtain the necessary steam by a connection within the smoke-box leading from the exhaust pipe of the main engine, while live steam for the operation of the former is preferably obtained from within the smoke-box, where connection may be conveniently made to either the saturated or superheated steam side of the superheater, as may be desired.

As the auxiliaries referred to are placed on the outside of the locomotive, it is necessary to lead the steam pipes through the smoke-box shell, and because of the existing equipment already within the smoke-box, the satisfactory arrangement of these steam pipes becomes a matter of considerable difficulty. Among the most difficult of the auxiliaries to install satisfactorily is the feed water heater, and it is in connection with the installation of such a heater of the surface or so-called "closed" type that I have illustrated the present invention.

In this form of apparatus the boiler feed water is pumped through a nest of tubes enclosed in a suitable casing to which is admitted a portion of the exhaust steam from the main engine of the locomotive, the feed water being heated by condensing this steam. In order to dispose of the condensate from the heater it is necessary that it be placed high enough on the locomotive so that the condensate may drain by gravity into the tender tank, and this restriction, together with the restrictions imposed by existing equipment already on the locomotive, has necessitated the placing of the heater at the forward end of the locomotive and above the level of the water in the tender. Generally the heater has been placed transversely above the smoke-box shell ahead of the stack, but in this position the heater in some instances forms an objectionable obstruction

to the vision of the locomotive engineer, and because of the relative position of other elements of the locomotive equipment this location, while the best available, is not, in many instances, entirely satisfactory.

It is the object of the present invention, therefore, to provide means whereby the steam piping to a heater or other auxiliary may be simplified and positioned in a more desirable manner with reference to the other elements of the locomotive, and by virtue of this simplification to make possible the location of a steam consuming auxiliary on the boiler shell at the rear of the stack. A further object is to enable a heater to be placed longitudinally of the boiler and behind the stack where it will in no way cut down the line of vision from the locomotive cab. Another object of the invention is to provide a piping arrangement which will enable the steam supply pipes leading to an auxiliary to be retained in the smoke-box of the locomotive and to simplify and improve the connections necessary to allow the pipes to pass through the smoke-box shell. It is a further object to retain the steam pipes within the smoke-box shell while at the same time in no way interfering with the existing equipment therein or obstructing access to the forward tube sheet of the boiler from the front end of the locomotive. It is also an object of the invention to reduce to a minimum the possibility of air leakage into the smoke-box by reducing the number of openings in the smoke-box shell necessary for the accommodations of the steam pipes which must lead therefrom. Other and further objects of the invention will appear in connection with the following detailed description of an embodiment of the apparatus illustrated in the accompanying drawings in which Figure 1 is a fragmentary elevation partly in section of the forward end of a locomotive, illustrating my invention as applied to a feed water heater positioned behind the stack.

Figure 2 is a front elevation of Figure 1 with the smoke-box cover removed and certain parts shown in section for clearness, and

Figure 3 is a horizontal section taken through the locomotive stack, of a modification of my invention as applied to a heater positioned transversely in front of the stack.

Referring now to Figure 1, 10 indicates the forward end of the locomotive boiler,

and 11 the smoke-box thereof. The feed water heater 12 is of the usual closed type, the interior details of which form no part of the present invention and which need not be described in detail. The heater is suitably mounted on top of the boiler 10, and receives steam for heating purposes through the inlet 13. Feed water from the pump 14 is supplied to the heater through pipe 15 and 10 is delivered from the heater to the boiler through the feed pipe 16, the exhaust steam from the feed pump 14 being ordinarily delivered to the heater through the conduit 17. Pipe 18 carries the condensate from the heater by gravity to the tender or pump suction line.

The steam used to supply the heater is taken in accordance with the usual practice from the engine exhaust pipe 19 by means 20 of the steam pipes 20. It is necessary, in order that the smoke-box may be kept unobstructed for access to the forward boiler tube sheet, that the steam pipes 20 be kept away from the central portion of the section 25 of the smoke box, and in many instances these pipes are carried up to the heater outside of the smoke-box. Ordinarily the portion of the smoke-box in front of the exhaust pipe and stack is comparatively unobstructed, but between the stack and the forward flue sheet the main steam pipes 21, leading from the boiler to the engine cylinders, and the superheater header 21^a and units 21^b, preclude the possibility of bringing the 30 steam pipes 20 up to the heater inside the smoke-box shell between the stack and the flue sheet.

As may readily be seen from Figure 1, with the heater in the position behind the 40 stack, it is necessary for the steam supply pipe thereto to be carried to a position behind the stack and the present invention provides means whereby a satisfactory and practical steam connection may be made between 45 the exhaust pipe and the heater, which will leave the steam pipes in a desirable position and at the same time make possible a simplification of the piping where it passes through the smoke-box shell.

According to my invention as illustrated 50 in Figure 1, the steam pipes 20 are brought up inside the smoke-box shell forward of the stack in the comparatively clear space which is there available and as shown in 55 Figure 2, the pipes 20 are brought upward near the periphery of the smoke-box whereby the clearance for access to the boiler tube sheet is not reduced, as the pipes 20 do not extend inward from the smoke-box wall further than the steam pipes 21.

In order to bring the steam line supplying 60 the heater through the smoke-box shell, the ordinary holes through which the steam pipes would pass are dispensed with, and the steam connection to the heater on the outside

of the boiler is made through a member passing through the aperture in the smoke-box shell provided for the stack. As shown in Figure 1, the usual opening 22 in the top of the smoke-box shell over which the stack 70 is positioned, is made somewhat larger than the stack diameter. The stack 23 may be constructed in the usual manner having the ordinary skirt portion 24 extending through the opening in the smoke-box shell. Around 75 the stack is the supporting member 25 to which the stack is suitably fastened, and which is ordinarily formed with a flanged portion 26 secured to the smoke-box shell. In the form of my invention here illustrated 80 this member is formed with a passage 27 therein in the form of an interrupted annulus having suitable openings 28 at the forward end thereof to which are secured the upper ends of the steam pipes 20, these openings, as may readily be seen from Figure 1, opening downwardly into the interior of the smoke-box. At the rear of the stack 23 the passage 27 is provided with an upwardly extending opening 29, which is, in the embodiment shown, extended upwardly in the form of an integral conduit 30 connecting with the steam inlet 13 of the heater, although it may readily be understood that the passage 27 may terminate in a connection at 29 above 95 the flanged portion 26 of member 25, with a separate pipe connecting the opening 29 with the heater inlet 13.

By means of this construction it is possible to keep the steam pipes 20 in the comparatively clear forward portion of the smoke-box where they may follow closely the outline of the smoke-box shell and form no obstruction to access to the boiler. At the same time it is possible to retain these 100 pipes within the smoke-box where they are subjected to the high temperatures of the furnace gases passing therethrough, thus minimizing heat losses from these pipes and preventing condensation of the steam passing 105 to the heater. The necessity for the heavy lagging necessary for outside steam pipes is also eliminated.

The usual difficulties encountered in bringing steam pipes through the cylindrical 110 surface of the smoke-box is also avoided and a single connection is formed between the outlet from the member 25 and the heater. It will be readily apparent that the annular 115 passage 27 need not be made integral with the member 25 but may be in the form of a separate conduit below the level of the flange 26 connecting therewith at the point of the opening 29. In other words, one of the pipes 20 may be omitted if desired, and if conditions within the smoke-box permit, the connection 28 may be nearer the point 120 29 than is shown in Figure 1, the pipe 20 being made correspondingly longer. In any event, however, the flanged portion 26 125

of the member 25 forms the portion of the steam passage where it passes through the smoke-box shell and the usual double connection at this point eliminated, the only connections in the steam line being the ordinary flat flanged connections at 28, and similar connections between the outlet 29 and the heater.

In Figure 3, I have illustrated a modification showing my invention as attached in an installation where the heater is placed transversely of the locomotive ahead of the stack. In this instance, the member 25' is formed with an annulus 27' which extends around the forward portion of the stack rather than the rear portion. In this instance the steam pipes 20' are connected to the openings 28' which correspond to the openings 28 in the form shown in Figure 1. The outlet opening 29' is in this instance ahead of the stack and connects at 13' with the body of the heater 12'. As shown in the modified form, it is not necessary to carry the steam pipes behind the line of the stack, but by the use of my invention it is possible to bring the pipes 20' up through the interior of the smoke-box and to bring the steam connection therethrough without providing any additional opening in the smoke-box other than that which is normally required for the stack. As in the form shown in Figure 1, all openings through curved surfaces in the smoke-box are eliminated and the steam connections leading from the exhaust pipe to the heater are materially simplified.

The application of the present invention results in advantages not only in the manner in which the steam connections may be carried through the smoke-box, but by the elimination of additional openings in the smoke-box shell through which the steam pipes must be carried, the possible leakage of air into the smoke-box through such openings is eliminated. Ordinarily openings through the cylindrical shell of the smoke-box through which steam pipes are carried are difficult to keep tight and result in air leakage which has a detrimental effect on the drafting of the locomotive.

My invention also makes possible the improvement in the appearance of the locomotive by enabling pipes which otherwise would have to be carried outside the locomotive shell to be brought upward inside thereof.

It is to be clearly understood that the foregoing description is illustrative only and is not to be taken in a limiting sense as it will be obvious that many changes and variations in the specific structure illustrated may be made without departing from the spirit of the invention as defined in the appended claims.

What I claim is:

1. In apparatus of the class described,

a locomotive smoke-box having the usual flange supported stack and engine exhaust pipe therein, a boiler tube sheet at the rear of said smoke-box, engine steam pipes extending downwardly substantially at the periphery of and through said smoke-box forward of the flue sheet, an exhaust steam consumer located outside the walls of said smokebox and a steam pipe leading from said exhaust pipe to said consumer, said pipe extending upwardly through said smokebox substantially at the periphery thereof forward of said engine steam pipes and delivering steam to said consumer through a passage extending through said stack supporting flange, whereby the central portion of said smoke-box is left unobstructed by said pipe for access to said tube sheet.

2. In apparatus of the class described, a locomotive smoke-box having the usual flange supported stack and engine exhaust pipe therein, a boiler tube sheet at the rear of said smoke-box, engine steam pipes extending downwardly substantially at the periphery of and through said smoke-box forward of the flue sheet, an exhaust steam consumer located outside the walls of said smokebox, and a bifurcated steam pipe leading from said exhaust pipe to said consumer, the branches of said bifurcated pipe extending upwardly through said smoke-box, substantially at the periphery thereof forward of said engine steam pipes and delivering steam to said consumer through a common passage extending through said stack supporting flange, whereby the central portion of said smokebox is left unobstructed by said branches for access to said tube sheet.

3. In apparatus of the class described, a smoke-box shell having an aperture therein for the reception of the locomotive stack, said stack including a flanged supporting member positioned over said aperture, a steam consumer located outside the smokebox, a source of steam located within the smoke-box, and a steam passage leading from said steam source to said consumer, said passage including a portion integral with said flanged member and passing there-through.

4. In apparatus of the class described, a locomotive stack supporting member having a central opening through which the locomotive stack passes and a flanged portion adapted to be positioned over an aperture in a smoke-box shell, said flanged portion including a steam passage extending there-through.

5. In apparatus of the class described, a locomotive stack supporting member having a central opening through which the locomotive stack passes and a flanged portion adapted to be positioned over an aperture in a smoke-box shell, said flanged portion having an opening there-through forming a

portion of a steam passage integral with said member.

6. In apparatus of the class described, a locomotive stack supporting member having a central opening through which a locomotive stack passes, a flanged portion adapted to be positioned over an aperture in a smoke-box shell, said member including a bifurcated steam passage extending from a point above said flanged portion through the latter, around said stack, and terminating in a pair of steam connections below said flange.

7. In apparatus of the class described, a locomotive smoke-box shell having an aperture therein, a locomotive stack passing through said aperture, said aperture having a dimension substantially larger than the diameter of said stack, whereby an opening is provided between said stack and shell, and a stack supporting member having a flanged portion overlapping said shell to close said opening and including a steam passage integral with the flanged portion and extending there-through.

8. In apparatus of the class described, a locomotive smoke-box shell having a stack passing there-through, an engine exhaust pipe located under said stack, a feed water heater located outside the smoke-box longitudinally behind said stack, a supporting member surrounding said stack and having

a flanged portion resting on said shell, said member having a bifurcated steam passage therein terminating at one end in a steam connection outside said smoke-box connected to said heater, and terminating at its other ends in a pair of steam connections within said smoke-box, and pipes supplying steam from said exhaust pipe to said last mentioned connections.

9. In apparatus of the class described, a locomotive smoke-box shell having a stack passing there-through, an engine exhaust pipe located under said stack, a feed water heater located outside the smoke-box longitudinally behind said stack, a supporting member surrounding said stack and having a flanged portion resting on said shell, said member having a steam passage therein comprising a pair of branches opening at their forward ends within the smoke-box forward of the center of said stack, extending around said stack at either side thereof and joining in a single branch extending through said flange at the rear of said stack, a connection from said latter branch to said heater, and a pair of steam pipes connecting said exhaust pipe with said branches, said pipes extending upwardly within said smoke-box near the periphery thereof and forward of the center of said stack.

CHARLES R. HARDY.
